Primary Examiner — Lauren R Calve(74) *Attorney, Agent, or Firm* — JoAnn M. Seaton;
Griffiths & Seaton PLLC(57) **CLAIM**

The ornamental design for a hanger sock, as shown and described.

DESCRIPTION

FIG. 1 is a bottom, front perspective view of a hanger sock showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof; and,

FIG. 8 is a top, front perspective view of the hanger sock of FIG. 1 shown during optional use with environmental subject matter indicated in broken lines.

The features shown in broken lines are portions of the hanger sock forming no part of the claimed design.

1 Claim, 4 Drawing Sheets(56)
